H. A. TENENT,
TROUSERS PRESSER,
APPLICATION FILED FEB. 10, 1917.

1,243,361.

Patented Oct. 16, 1917.

UNITED STATES PATENT OFFICE.

HUBBARD A. TENENT, OF CHICAGO, ILLINOIS.

TROUSERS-PRESSER.

1,243,361.

Specification of Letters Patent. Patented Oct. 16, 1917.

Application filed February 10, 1917. Serial No. 147,757.

To all whom it may concern:

Be it known that I, HUBBARD A. TENENT, a citizen of the United States, residing at Chicago, in the county of Cook and State 5 of Illinois, have invented certain new and useful Improvements in Trousers-Pressers, of which the following is a specification.

This invention relates to trousers pressers in which the trousers or other garments are 10 pressed between two plates. The object of the invention is to provide suitable and convenient means for manipulating the plates in applying and removing the trousers and in producing suitable pressure on the same 15 wherever pressure may be desired.

The invention is an improvement on my invention which is illustrated and described in the Patent No. 796,471 issued to me August 8, 1905, and reference to said patent 20 may be had for a more particular description of the invention covered thereby.

Of the accompanying drawings Figure 1 is a plan view of the presser when opened. Fig. 2 is a section taken along the line 2—2 25 of Fig. 1. Fig. 3 is an enlarged fragmental section taken along the line 3—3 of Fig. 1, but with the presser closed. Fig. 4 is a similar section along the line 4—4 of Fig. 1. Fig. 5 is a plan of one of the clamps of the 30 presser, and Fig. 6 is a side view of Fig. 4.

The trousers to be pressed are first dampened, and are then placed upon the plate 6, with the legs extending toward the narrow end of the plate, and with the cuffs, if any, 35 placed on the extension 7 of the plate, the upper surface of this extension being offset downwardly from the upper surface of the plate sufficiently to allow room for one half of the thickness of the cuffs in excess of the 40 thickness of the pants. The lower end of the trousers may then be held in place by a strap 8 and a clip 9 holds the upper portion of the trousers in place particularly when the presser is being closed, or is being opened 45 to remove the trousers. The upper plate is then turned down on the trousers, being hinged to the lower plate by means of hinges 11, and the two plates are then pressed firmly together by means of clamps 12 and 50 13, the upper side of the cuffs passing into the space formed by the offsetting of the extension 14 of the upper plate.

The plates may be made of any suitable material and shape. I prefer for the purpose

thin sheets of wood firmly adhering to a 55 central sheet 16 of wood, as such an arrangement eliminates the warping which would occur if the plates comprised single sheets. The extensions 7 and 14, however, I prefer to make of metal, so that the thickness may 60 be materially reduced. On the adjacent surfaces of the plates and the extensions are sheets 17 of any suitable cloth material. These cloth sheets provide cushioning means for the trousers and absorb the moisture 65 therefrom.

Each hinge 11 comprises plates or straps 20 and 21 pivoted together in any suitable manner, strap 20 being fixed to the outer surface of plate 6, and strap 21 extending, 70 as shown in Fig. 4, through an opening 22 in a strap 23 which is fixed to the outer surface of plate 10. Pivoted to the free end 24 of the strap 21 is an eccentric clamp 13, which when the plates are closed is adapted 75 to press down on the strap 23 and force the plates firmly together by turning the arm 26 in one direction, but which when the arm is thrown in the opposite direction releases the plates and allows them to be opened. By 80 these means provision is made in an exceedingly simple manner for the hinging and the clamping of the two plates and for allowing them to separate when closed sufficiently to include trousers of any thickness. 85

Each clamp 12 is hinged to the plate 6 by means of a strap 28 fixed to the outer surface of the plate and a strap 29 pivoted in any suitable manner to the strap 28, the eccentric clamp 12 being pivoted to the free 90 end of the strap 29. Fixed to the outer surface of the plate 10 is a strap 30 which forms a seat for the eccentric, as indicated in Fig. 3; and a flange 31 projecting from the strap 30 locks the eccentric in place preventing it 95 from slipping sidewise from the strap 30. And projections 32 each side of the strap 29 prevent longitudinal displacement of the strap.

Shoulders 33 on the strap 21 prevent the 100 strap 22 from sliding down on the strap 21 too far toward the hinge when the presser is opened, and springs 34 hold the plates apart when the presser is being closed so as to prevent the plate 10 from displacing any portion of the trouser as the plate descends thereon, the springs, while sufficiently strong to hold the plates apart, are easily overcome 105

by the action of the clamp. And the clip 9 also assists in holding the trousers from displacement as the plate descends.

I claim as my invention:

- 5 1. In a press, two plates, two of the edges of said plates being rotatably but loosely connected, and means for clamping and locking the opposite edges of said plates together, said means comprising a strap fixed to each of said plates, a third strap pivoted to one of said straps, the other of said straps having a flange projecting outwardly therefrom adjacent the edge of the plate, and a clamp fixed to the free end of said third strap, said clamp adapted to press on said flanged strap adjacent said flange with the flange positioned between said clamp and said third strap, and means to prevent longitudinal movement of said clamp.
- 10 2. In a press, two plates, two of the edges of said plates being rotatably but loosely connected, and means for clamping and locking the opposite edges of said plates together, said means comprising a strap fixed to each of said plates adjacent one edge thereof, a third strap pivoted to one of said two straps, a clamp fixed to the free end of said third strap and adapted to press on the other of said two straps, and means to prevent longitudinal or transverse movement of said clamp on said latter strap.
- 15 3. In a press, two plates, two of the edges of said plates being rotatably but loosely connected, means for clamping and locking the opposite edges of said plates together, said means comprising a strap fixed to each of said plates, a third strap pivoted

25 to one of said straps, the other of said straps having a flange projecting outwardly therefrom adjacent the edge of the plate, and a clamp fixed to the free end of said third strap, said clamp adapted to press on said flanged strap adjacent said flange with the flange positioned between said clamp and said third strap, and means to prevent longitudinal movement of said clamp.

30 35 40 45 3. In a press, two plates, two of the edges of said plates being rotatably but loosely connected, means for clamping and locking the opposite edges of said plates together, said means comprising a strap fixed to each of said plates adjacent one edge thereof, a third strap pivoted to one of said two straps, a clamp fixed to the free end of said third strap and adapted to press on the other of said two straps, and means to prevent longitudinal or transverse movement of said clamp on said latter strap.

In testimony whereof, I hereunto set my hand.

HUBBARD A. TENENT.
